(57) **CLAIM**

The ornamental design for a cladding for building as shown and described.

DESCRIPTION

1.1 is a top view of a cladding for building in accordance with the invention;

1.2 is a perspective view of a cladding for building in accordance with the invention;

1.3 is a perspective view of a cladding for building in accordance with the invention;

1.4 is a perspective view of a cladding for building in accordance with the invention;

1.5 is a perspective view of a cladding for building in accordance with the invention;

1.6 is a perspective view of a cladding for building in accordance with the invention;

1.7 is a perspective view of a cladding for building in accordance with the invention;

2.1 is a perspective view of a cladding for building in accordance with the invention;

2.2 is a perspective view of a cladding for building in accordance with the invention;

2.3 is a top view of **2.1**;

2.4 is a right side view of **2.1**;

2.5 is a bottom view of **2.1**;

(Continued)

2.6 is a left side view of 2.1; and
2.7 is a front view of 2.1.

1 Claim, 14 Drawing Sheets
